CARD-SORTING MACHINE

Harold P. Mixer, Rockville Centre, N. Y., assignor
to Remington Rand Inc., New York, N. Y., a
corporation of Delaware

Application September 18, 1948, Serial No. 49,929

2 Claims. (Cl. 209—110)

1

This invention relates to card sorting machines, and more particularly to machines for grouping cards having alphabetic data perforated therein in accordance with well known accounting and statistical analyzing systems.

The invention as herein illustrated is directed to improvements in business machines for sorting cards similar to those disclosed and described in the patents to W. W. Lasker 1,815,370 issued September 9, 1919, and 2,044,120 issued June 16, 1936.

Sorters of this type, up to the time of the instant invention, have been inefficient in the sorting of cards perforated in a combinational hole code indicating the alphabet. To sort cards of this type, it has been necessary to pass the cards through the machine at least three times for each column of data to group the cards in alphabetic sequence. This resulted in undue wear on the cards, shortening their life.

The present invention is directed to improvements in sorting machines whereby cards, perforated with combinational hole code representing alphabetic data, are sorted after being passed through the machine but twice for each column of data.

The principal object of this invention, therefore, is to provide an improvement whereby the number of operations necessary to sort cards perforated in combinational hole alphabetic code is reduced.

Another object of this invention is to provide a machine whereby cards perforated in combinational alphabetic code may be efficiently sorted, without undue wear on the cards.

A still further object is to provide a simple attachment whereby existing machines may be improved to efficiently sort cards perforated with combinational alphabetic code.

A more clear conception of the operation, construction, and further objects of the invention may be had from the following specification when read in conjunction with the accompanying drawings, in which:

Fig. 1 is a sectional view illustrating an embodiment of the invention;

Fig. 2 is a front elevational view of the interpreter unit;

Fig. 3 is a cross section of Fig. 2 taken along the medial line thereof, showing only those parts which are effective when the interpreter unit is in position for the second run;

Figs. 4, 5, and 6 are similar to Fig. 3, with certain parts shown in operated position;

Fig. 7 is a detail showing the mounting for one of the interponents of the interpreter cage;

Fig. 8 is an enlarged isometric detail of a portion of Fig. 7;

Fig. 9 is a diagram showing the interpreter

unit in the position for a first run of the machine in sorting cards;

Fig. 10 is a diagram similar to Fig. 9, showing the parts in position for a final run of cards;

Fig. 11 is an exploded isometric view of a portion of the firing lever control latches, particularly the "nines" control mechanism; and

Fig. 12 shows a portion of a card perforated with a combinational hole code representing alpha.

The invention is embodied in a machine for sorting cards similar to that shown and described in the above mentioned patents, and more particularly in 2,044,120. In view of this fact only 15 that much description of the sorter necessary for an understanding of the invention will be given, and reference characters similar to those in the patent will be used wherever possible.

A reciprocating pin box containing twelve pins 20 senses one column of a card. The action of a pin entering a hole in the card is transmitted over a Bowden wire to a settable wiring unit or interpreter, which in turn transmits the action to a selected gate over a pocket into which the 25 card, upon being fed, is directed. The wiring unit has two positions, viz., one in which single hole code is interpreted, and the other in which combinational hole code is interpreted or translated. In the terminology of these codes the single hole code is identified as the forty five column code, and the combinational as the ninety column code.

The present invention lies in the modification of the wires in the forty five column portion of 35 the rotating cage of the interpreter unit, as disclosed in the Patent 2,044,120, the wires in the ninety column portion being unchanged.

The Bowden wires 27 (Fig. 1) leading from the sensing unit (not shown) are anchored in 40 a plate 66 and actuate bell-cranks 43 pivoted on a cross shaft 44 carried in a frame 40 secured to the frame of the sorter. There are twelve bell-cranks 43a to m, inclusive, one for each sensing position. Mounted in the frame pieces 45 40 is a rotatable cage or interpreter unit 56 which will be described later. Loosely mounted on a cross shaft 53 above the cage is a plurality of latches 54 which coact with firing levers 46a, b, d, e, f, and g, which are loosely pivoted on a 50 shaft 48 (Figs. 9 and 10). Mounted alongside each firing lever 46 is a firing lever 47a, b, c, d, e, and f, respectively, of slightly different shape. A latch 71 (Fig. 11) coacts with lever 47c, which is known as the "nines" firing lever. The 55 latches 54 are connected to wires from the "zero," "one," "three," "five," and "seven" positions in the code, while latch 71, of which there is only one, is connected to the interpreter wire from the "nine" position. Cooperating with a nose 60 on the bell-crank 47c is a universal bail 72 loosely

mounted on shaft 53, which bail coacts with and is spring connected to latch 71. The lower ends of all firing levers 47 are formed with hooks which underlie the bail 72 so as to prevent their operation, even though one or more latches 54 may have been released. On a "nines" operation, i. e., the sensing of a hole in the "nine" position, the bail 72 is rocked out of the path of the hooks on bell-cranks 47, permitting their operation. The firing lever 47c operates to open the gate of the number nine pocket.

At times during combinational sorting two or more Bowden wires 27 may operate simultaneously, the one actuating a latch 71, and the others operating one or more latches 54. In this event the following elements will modify the operation: The forwardly extending nose of each latch 54 is in contact with bail 74 pivotally mounted on a shaft 53 and spring pressed into engagement therewith. Journaled on the shaft 53 alongside the latch 71 is a special latch 75 which is spring connected to the bail 74 by a spring 76, causing members 74 and 75 to move in unison. The "nines" firing lever 47c is provided with a pin 77 extending in the path of a hook on the upper edge of the latch 75. It is engaged when the latch rocks counter-clockwise. Hence, rocking of any trigger 54 by any interpreter wire 61 or 62 (except nine) causes the special latch 75 to lock the "nines" firing lever 47c against operation. Bail 72 rises with the operation of a "nines" interpreter wire, releasing firing levers 47 for operation, and blocking levers 46, because it now lies in the path of their extreme lower ends.

Summarizing, an odd interpreter wire (except zero and nine) rocks a latch 54 to release two firing levers 46 and 47. If the "nines" interpreter wire 61 is not operated, the bail 72 remains normal and blocks the members 47 against operation, but if the "nines" wire is operated, bail 72 is elevated by the operation of the special latch 71 and the members 47 are released while members 46 are blocked.

The interpreter cage 56 (Figs. 1 and 2) consists of a pair of end members in the form of discs 26 held in relation to each other by four perforated bars 57 and 58, and a pair of cross rods 60, thus making a rigid cage for supporting and guiding the interponents or interpreter wires 61 and 62 which constitute card pocket selecting means. The interpreter wires 61 are of the same form and layout as those shown in Patent 2,044,120. The wires 62 have been adapted for the work to be performed by the invention. The discs 26 are provided with pintles 55 which ride in notches cut in the frames 49. The cage is provided with a handle 65, by which it may be positioned in either of its operating positions.

The interponents 62 are formed as shown in Figs. 2 to 7, inclusive. There are only four wires, viz., 62a, b, c, and d, inclusive. Wire 62a is fastened in a block having two pins thereon (Fig. 10) one of which cooperates with bell-crank 43a and the other with bell-crank 43b. Wire 62b is fastened in a block having two pins therein, one of which cooperates with bell-crank 43c and the other with 43d. This block is formed with an arm 20 having a turned over lug 21 thereon. The wire 62d is fastened in a similar block, the pins of which cooperate with bell-cranks 43k and 43m, respectively. This block has an arm 22 with a turned over lug 23 thereon. The auxiliary wire 62c is secured in a block

fastened to a box like structure 24. The structure is formed of one piece of metal bent to form a box, the ends of which are closed by plates 25. A pair of brackets 30 secured to a cross bar 57 forms a slidable mount for the structure 24, which is secured thereto by screws 31 extending through slots 32. A pair of slots 33 are formed in the front wall of the box 24 to accommodate the lugs 21 and 23 on arms 20 and 22. Positioned loosely in the box 24 are three tumblers 34, 35, and 36. The tumblers 34 and 36 are spacers to center the operating tumbler 35. As seen in Figs. 4 and 6, the construction is such that if either one or the other of the lugs 21, 23 are raised they will pass idly between the tumblers. However, if both lugs are raised together (Fig. 5) they will carry the tumbler 35 between them and raise the tumbler housing 24 and its associated auxiliary interponent 62c.

In Fig. 12 is shown a card perforated in accordance with the ninety column or combinational hole code. The card is customarily divided into upper and lower zones, each containing forty-five columns of six index positions. Fig. 12 shows only a portion of the upper zone of a card. These index positions, for convenience of description, will be known as the "zero," "one," "three," "five," "seven," and "nine" positions.

For the first run of the machine, while sorting with the invention, the interpreter cage is set in position "A" (Figs. 1 and 9). Let it be assumed, as an illustration, that the sensing pins find perforations in the "one," "five," and "nine" positions of the upper zone, which, it will be seen by reference to Fig. 12, represents the letter "A." Referring to Fig. 9 it will be seen that Bowden wires 27i, 27d, and 27f will be actuated by such a coding. These wires in turn will rock bell-cranks 43i, 43d, and 43f, respectively, which will raise interpreter wires 61e, 61b, and 61c. This action will unlatch firing levers 46b, 47b, 46f, 47f, and 47c, whereupon the "nines" mechanism associated with firing lever 47c (Fig. 11) will, as described above, withhold levers 46f, 47c and 46b, and result in levers 47b and 47f being fired. These levers will actuate Bowden wires 29c and 29j leading to the gate control for the "two" and "six" pockets, respectively. The opening of the "six" pocket will have no effect at this time, as the card will reach the "two" pocket first in its travel through the machine, and be directed into that pocket which is the desired pocket.

Any attempt to describe in detail the operation for each and all letters of the alphabet during this first run would unduly prolong the specification, without adding clarity thereto. It may be said that the operation for each is the same, and the following table shows the pockets into which the different cards will be directed, and in which they will be found at the end of the first run:

Reject	9	8	7	6	5	4	3	2	1	0	11	12
L	X			N	G	K	Q	F	R	C		
				Z		T	I	A	S	E		
						V	H	Y	B	W		
									J	D		
									O	M		
									P	U		

A rolling stand having a plurality of pockets, similar in shape to those of the sorter, designated from "zero" to "twelve" and "A" to "Z" is usually provided to hold the cards withdrawn from the pockets of the sorter after the first run. The cards are thus easily held segregated

in accordance with the pockets from which they are removed, i. e., the cards from the "zero" pocket are placed in the "zero" pocket of the stand, etc. It will be noted that the cards containing the letters "L," "X," and "G" have already been segregated into the "Reject," "eight," and "five" pockets, respectively, and, therefore, can be placed directly in the pockets of the stand designated "L," "X," and "G."

Before starting the second run of the sorting operation, the interpreter cage is rocked to position "B" (Figs. 1 and 10) bringing the interpreter wires 62 into operative position.

Only those cards from the "zero" pocket in the previous run are now placed in the machine. Among these are cards containing perforations in the "zero," "three," and "five" positions representing the letter "D." The sensing of these perforations will actuate Bowden wires 27h, 27m, and 27d which, in turn, will rock bell-cranks 43h, 43m, and 43d, respectively. Bell-crank 43h will have no effect, as there is no dependent pin in this position on block 62c. Bell-crank 43m will raise wire 62d, and bell-crank 43d will raise wire 62b. As both of these wires have arms 20 and 22 with lugs 21 and 23 thereon, they will engage the tumbler 35 and raise the auxiliary wire 62c together with its associated wires 62b and 62d (Fig. 5), thus actuating firing levers 46f, 47f, 46d, 47d, 46b, and 47b. However, since lever 47c is not actuated the 47 firing levers will be blocked, and the lever 46f will actuate Bowden wire 29k to open the "five" pocket. Lever 46d will open the "three" pocket over Bowden wire 29g, and lever 46b will actuate Bowden wire 29d to open the "one" pocket. Due to the fact that the "one" pocket is reached by the card first, it will be guided therein. The remainder of the cards taken from the "zero" pocket will be distributed as shown in the table below.

Reject	9	8	7	6	5	4	3	2	1	0	11	12
	C			U	M	W	E					

The cards taken from the "one" pocket are next placed in the machine, and among these cards are some perforated in the "one" and "five" positions, representing the letter "B." The sensing of these positions will actuate Bowden wires 27i and 27d, which will rock only bell-crank 43d, as there are no dependent pins associated with bell-crank 43i which is actuated by wire 27i. Bell-crank 43d will raise wire 62b (Fig. 6), the lug 21 of arm 20 thereon passing idly between tumblers 34 and 35. Wire 62b will unlatch firing levers 46f and 47f. As lever 47c is not operated, lever 47f is held and 46f fires actuating Bowden wire 29k, opening the "five" pocket to receive the cards perforated with the letter "B." The remainder of the cards taken from the first pocket will be found in the pockets shown in the table below.

Reject	9	8	7	6	5	4	3	2	1	0	11	12
	R			S	B	P	O					

Of the cards taken from the "two" and "three" pockets after the first run, there are some perforated in the "three," "five" and "seven" positions representing the letter "Q" which will actuate the interpreter wires 62a, 62b, and 62d. This will cause all wires 62 (Fig. 3) to be raised, resulting in the blocking of firing levers 46, and only levers 47b, 47c, and 47f will fire, resulting in the opening of pockets "two," "four," "six," and "nine." The card enters the "two" pocket as

shown in the table below, which also shows the distribution of the other cards.

Reject	9	8	7	6	5	4	3	2	1	0	11	12
	F			A	H	Y	Q	I				

5 Cards taken from the "four" and "six" pockets during the first run will be distributed to the following pockets during the second run.

Reject	9	8	7	6	5	4	3	2	1	0	11	12
	Z	N	T	U		K						

10 From the above it is seen that the cards are easily and efficiently sorted alphabetically without undue wear on the cards.

15 While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention 20 as hereinbefore set forth, and as hereinafter claimed.

25 What is claimed as new, and desired to secure by Letters Patent, is:

25 1. A device for transmitting movement from operating means controlled by a card sensing mechanism to another group of operating means for controlling the pocket gates of a sorting device comprising a holder, interponents under control of said sensing mechanism slidably mounted in 30 said holder for register at their opposite ends with said groups of operating means, a normally inactive auxiliary interponent inoperable by said sensing mechanism for register with said gate operating means, a tumbler housing connected to said interponent, a tumbler in said housing, and projections on said interponents for engaging the tumbler, said tumbler being movable out of the path of the projections of individually operated interponents and being movable to a position 35 between said projections when the interponents are operated in unison through said sensing mechanism to actuate said normally inactive auxiliary interponent and gate operating means.

40 2. In a machine for sorting cards employing 45 single and combination code perforations including hole sensing means, card pocket gate operating means, an interpreter cage for transmitting movement from the sensing means to said operating means, a plurality of transmitting interponents in said cage operable individually to transfer movement between a single sensing means and a single gate operating means and operable in combination to transfer movement 50 between a pair of sensing means and a plurality of gate operating means, a normally inactive auxiliary transmitting interponent inoperable by 55 said sensing means in said cage for moving a gate operating means, said interponent having a tumbler housing thereon and by the concurrent 60 movement of a plurality of interponents operable in said tumbler housing by a combined movement of said transmitting interponents for actuating a gate operating means.
